UNITED STATES PATENT OFFICE.

MARK A. DEFIBAUGH, OF SCHENECTADY, NEW YORK, ASSIGNOR TO L. E. CASE, INC., OF SCHENECTADY, NEW YORK, A CORPORATION OF NEW YORK.

DESIGN FOR A COMBINED TABLE AND CASING FOR A WASHING MACHINE OR THE LIKE.

Application filed March 15, 1928. Serial No. 25,855. Term of patent 14 years.

To all whom it may concern:

Be it known that I, MARK A. DEFIBAUGH, a citizen of the United States of America, residing at Schenectady, in the county of Schenectady and State of New York, have invented a new, original, and ornamental Design for a Combined Table and Casing for a Washing Machine or the like, of which the following is a specification, reference being had to the accompanying drawing, forming part thereof.

The figure is a perspective view of a combined table and casing for a washing machine, showing my new design.

I claim—

The ornamental design for a combined table and casing for a washing machine or the like, as shown.

In testimony whereof I hereto affix my signature.

MARK A. DEFIBAUGH.

CERTIFICATE OF CORRECTION.

Design Patent No. 75,830.

Granted July 24, 1928, to

MARK A. DEFIBAUGH.

It is hereby certified that the name of the assignee in the above numbered patent should have been written and printed as "L. E. Cass, Inc.", instead of "L. E. Case Inc.", as shown by the records of assignments in this office; and that the said Letters Patent should be read with this correction therein that the same may conform to the record of the case in the Patent Office.

Signed and sealed this 25th day of September, A. D. 1928.
